UNITED STATES PATENT OFFICE

172,584

CUTLERY SET TRAY OR SIMILAR ARTICLE

Donald H. Dew, Fayetteville, N. Y., assignor to
Aluminum Company of America, Pittsburgh,
Pa., a corporation of Pennsylvania

Application June 26, 1953, Serial No. 25,678

Term of patent 7 years

(Cl. D44—29)

To all whom it may concern:

Be it known that I, Donald H. Dew, a citizen of the United States, residing at Fayetteville, in the county of Onondaga and State of New York, have invented a new, original and ornamental Design for a Cutlery Set Tray or Similar Article, of which the following is a specification, reference being had to the accompanying drawings, forming a part thereof, in which:

Fig. 1 is a top plan view of a cutlery set tray showing my new design;

Fig. 2 is a side elevational view thereof; and

Fig. 3 is a cross sectional view taken on the line III—III of Fig. 2.

I claim:

The ornamental design for a cutlery set tray or similar article, substantially as shown.
